SELECTIVE POSITIONING, STACKING, AND FEEDING MACHINE

Alfred Gausman, West Hempstead, N. Y., assignor to Henry Heide, Incorporated, New York, N. Y., a corporation of New York

Application January 25, 1951, Serial No. 207,690

8 Claims. (Cl. 198—30)

The present invention relates to a machine for assembling candy wafers or the like into stacks preparatory either to being wrapped automatically or by hand. More particularly, the present invention provides a selective positioning and feeding machine of this type which may be charged with two or more types or colors of wafers and which will automatically deliver the same in stacks to the initial station of a wrapping machine, with the wafers in preselected positions according to their respective colors or other characteristics.

In the candy industry, and particularly in the manufacture of cream mints of two or more colors, such for instance as the familiar white and pink variety of cream mints, the product is customarily offered for sale in five cent packages of seven or more mints in stacked relation which are wrapped in transparent packaging material such as wax paper, "cellophane" and the like. The appearance of the product is greatly enhanced if the mints are alternately arranged by color.

Prior to the present invention it had been common practice to manually arrange the mints in alternate colors in individual stacks. This is a costly and tedious operation. Furthermore, it had been common practice to manually deliver such stacked mints to the first station of a wrapping machine.

It is an object of the present invention to provide a machine which will automatically select, position, stack and feed two or more products of different characteristics (such, for instance, as two different colors of mints) in a predetermined arrangement and will deliver the same to the initial station of a wrapping machine and thereby eliminate the costly and tedious manual operations heretofore required for this purpose.

According to the present invention there is provided an endless conveyor the active component of which is normally disposed in a horizontal plane, said conveyor being formed on its upper surface with a plurality of arms, which travel between longitudinally extending partitions disposed above the conveyor to provide commodity-receiving pockets arranged in transverse and longitudinal rows, said conveyor passing beneath two or more commodity-delivering sources from which commodities having different characteristics are adapted to be delivered to the pockets, means being provided adjacent the first commodity source to enable such commodities to be fed into only preselected pockets and means being provided beneath the second commodity source to cause the commodities from said second source to enter only other preselected pockets in the endless conveyor, whereby said commodities of different characteristics are positioned in a predetermined arrangement and are fed to a discharge station in both stacked and selectively-positioned arrangement ready for delivery to the first station of an automatic packaging or wrapping machine. The present invention also provides a transfer wheel which operates in timed relation with said conveyor and receives successively therefrom one stack of commodities and delivers the same to the first station of a conventional type of wrapping machine.

The foregoing and other features of the invention, not specifically recited, will be more readily understood from the accompanying drawings which illustrate one embodiment of the invention, wherein:

Figure 1 is a side elevation of a machine of the present invention;

Fig. 2 is a sectional view of the machine in substan-

tially end elevation taken along the line 2—2 of Figure 1, and looking in the direction of the arrows;

Fig. 3 is a plan view of the machine of Figure 1;

Fig. 4 is a perspective view of a wrapped package of mints stacked and arranged in alternate colors by the machine of the present invention;

Fig. 5 is a perspective view of the transverse right-angled members forming part of the longitudinally movable conveyor;

10 Fig. 6 is an enlarged fragmentary plan view of the machine partially broken away to show underlying structure;

Fig. 7 is a longitudinal section taken along the broken line 7—7 of Fig. 6, and viewed in the direction of the arrows, the conveyor elements and the mints being shown in elevation.

Fig. 8 is a sectional view taken along the line 8—8 of Fig. 7, viewed in the direction of the arrows;

20 Fig. 9 is a similar sectional view taken along the line 9—9 of Fig. 7, viewed in the direction of the arrows;

Fig. 10 is an enlarged side elevation, with parts broken away, of the transfer wheel and associated parts of the wrapping machine shown at the left of the machine in Figure 1; and

25 Fig. 11 is a section taken along the line 11—11 in Fig. 10, and viewed in the direction of the arrows.

In order to simplify the present description, the invention as illustrated in the drawings will be herein described in the form in which it would be used for stacking eight cream mint disks of two colors, pink and white, for selectively positioning them alternately by pink and white, and for feeding them and delivering them in such stacked and alternate color arrangement to the first station of a "Lynch" automatic wrapping machine of the type which is shown in United States Letters Patent No. 2,336,752. It will be understood, however, that the machine of the present invention is not limited in its application to the handling of cream mints; nor is it limited to selective positioning by color; nor is it limited to the selective positioning of only two commodities having different characteristics.

As seen from the drawings, the machine comprises a table 10 having side rails 11 and end frame members 12 suitably supported by legs 13 (Figs. 1 and 2). Journaled in suitable bearings 14, 15 (Fig. 2) is a drive shaft 16 driven through mitre gears 17, 18 from a power source (not shown) by a power drive shaft 19. Secured to the drive shaft 16 and mounted on a shaft 20 in suitable bearing supports 21 mounted on an end frame member 12 are a pair of sprocket wheels 22, 23, respectively, the sprocket wheel 23 being driven by a sprocket chain 24 and normally rotated continuously in the direction of the arrow in Fig. 1. Also fixedly mounted on the shaft 20 is a pair of axially spaced sprocket wheels 25, 26. A second pair of sprocket wheels 27, 28 are correspondingly disposed on a shaft 29 supported in bearings 30 affixed to the end member 12 at the opposite end of table 10.

Two endless roller chains 31, 32 disposed in substantially parallel relation engage the teeth of each pair of sprocket wheels disposed on opposite sides of the table 10, the chain 31 engaging over sprocket wheels 25 and 27 and the chain 32 engaging over sprocket wheels 22 and 28. As best seen in Figs. 6 to 9, the chains 31, 32 carry a plurality of right-angled members 33 disposed transversely of said roller chains to which they are secured by offset lugs 33a on the chain links by rivets or the like, said right-angled members having substantially continuous bases 34 which extend laterally across and between the chains and having upstanding flange portions 35 which are cut out, as shown at 36, to provide a plurality of spaced upstanding fingers 37, for a purpose which will presently be made apparent. The several right-angled members 33 are disposed with their base portions 34 in spaced relation, as shown in Figs. 6 and 7, the spaces therebetween being partially filled by transverse cross-bars 38 which are also secured to the links of the roller chains 31, 32. The parts 31 to 38 constitute a conveyor which, for convenience of reference, is designated 39.

As best seen in Figs. 1 and 3, a first commodity bin

or hopper 40 is suitably supported above and to one side of the conveyor 39 and constitutes a first filling station, generally designated A. The first commodity bin 40 is provided with a downwardly sloping chute 41 which terminates in a horizontal base 41a overlying the conveyor and facilitates feeding the first commodity which, for illustrative purposes, shall be deemed to be white cream mints 42. A second commodity bin or hopper 43 having a downwardly sloping chute 44 which terminates in a horizontal base 44a overlying the conveyor is suitably positioned and supported at the second filling station, referred to generally as B, whereat the second commodity is delivered to the conveyor 39. For convenience the second commodity will be described as pink cream mints 45.

It will be seen from Figs. 3, 6, 8 and 9 of the drawings that a plurality of vertically disposed partitions 50 are provided which extend the full length of the table and that the upstanding fingers 37 of the right-angled members 33 pass between these partitions, the latter being disposed in the cut-outs 36 which are provided in the flange portions 35. It will thus be apparent that the conveyor 39, in conjunction with the partitions 50, provides a plurality of individual commodity-receiving pockets 51 and 52 which are defined by alternate pairs of partitions 50 and by the upstanding fingers 37, said pockets being arranged in both transverse and longitudinal rows. In the form of the invention illustrated, eight such pockets provide each transverse row.

Referring now to Fig. 8 of the drawings, which shows a section taken along the line 8—8 of Fig. 7, or in other words an end view of that portion of the conveyor and hopper 40 constituting the first filling station A, it will be noted that the bottom 41a of the bin or hopper 40 constitutes a platform which overlies, is adjacent and communicates with a plurality of triangular shaped hoods or covers 55 spanning each alternate pair of partitions 50, thereby closing off the alternate longitudinal rows of pockets above the conveyor from the receipt of commodities from the first commodity bin 40. In this connection it will be noted that the triangular shaped hoods or covers 55 not only prevent the admission of commodities into certain rows of pockets but they also serve to facilitate, because of their inclined sides, the entry of commodities 42 from the base 41a of hopper 40 into the pockets 52 provided in the uncovered rows of partitions 50. The triangular shaped hoods 55 preferably extend from the start of station A, designated by the line 56, to line 57 where such station ends and station B commences.

Referring now to Fig. 9 of the drawings which shows a section taken along the line 9—9 of Fig. 7, or in other words an end view of the conveyor and hopper 43 which constitute station B, it will be noted that a second plurality of triangular shaped hoods or covers 60 are provided which span the alternate partitions 50, such hoods 60 being staggered with relation to the hoods 55 and serving to close pockets 52 which have already received commodities from the first bin 40. Pockets 51 in turn are now exposed to commodity-receiving condition and such hoods 60 serve to facilitate the reception of the commodities 45 from the platform base 44a of the second bin 43 as the conveyor passes through the second filling station. The hoods 60 extend from the line 57, the start of station B to 61, the end of such station, to the start of what is termed for convenience station C, which ends at line 62, which is the start of an inclined delivery chute 63.

Any suitable means may be provided for feeding or moving the commodities from the bases 41a and 44a of the hoppers over the adjacent uncovered pockets 52 and 51, respectively. With a machine as disclosed, an operator brushes the cream mints over the hoods at the respective stations whereupon the mints drop into the pockets by gravity. Of course, automatic means may be employed to accomplish the same desired ends.

The partitions 60 are supported in spaced overlying relation to the conveyor 39 in part by the hoppers 40 and 43 (Figs. 8 and 9) which, in turn, are in part supported by side rails 64 held in spaced relation above table 10 by studs 65. Beyond the hoppers, that is, at station C, the partitions are supported by cross-arms 66 mounted on studs 67 secured to the top of the table 10.

It will be noted in the operation of the machine that

while the conveyor 39 is moving through station C, the commodity pockets 51, 52 are filled with cream mints which are disposed in upright position, the mints in the transverse rows being alternately disposed with respect to their colors. In this connection it should be stated that the mints are of a thickness to substantially fill the width between a pair of partitions 50, while the fingers 37 are narrower than the mints. While the conveyor is passing through this station the operator of the machine can make certain by visual inspection that each pocket has been filled with a cream mint or other commodity.

It will also be noted that station C, which is in a normally horizontal plane, terminates slightly outwardly of the common axis of sprocket wheels 25 and 26 and merges into the downwardly inclined chute 63 which is substantially tangential with the periphery of such sprocket wheels. As the right angle members 33 are carried by the conveyor over the sprocket wheels 25, 26, the upstanding fingers 37 act as pushers for driving each transverse stack of arranged mints down the chute 63, the latter being provided with a plurality of cut-outs or slots 68 in its base to permit the fingers to pass therethrough on their continued travel around the periphery of the sprocket wheels, as best shown in Fig. 10. The chute 63 is also provided with vertically disposed partitions or guides 69 in alignment at their upper end with the partitions 50 to maintain the color mints in the preselected arrangement while traveling down the chute. As best seen in Fig. 11 of the drawings, the guides or partitions 69 taper inwardly as they approach the base of the chute so as to bring the mints in more closely stacked relation at the place of transfer to the packaging machine. It will also be noted from Fig. 10 that as the right-angled members 33 travel around the periphery of the sprocket wheels 25, 26, the upstanding fingers 37 defining the ends of each pocket become spaced farther apart on radii of the sprocket wheels. Hence, in order to prevent the mints entering the then enlarged spaces, the cross-bars 38 previously mentioned come into play and maintain the mints in elevated position and spaced in substantially the same distance above the roller chain as the conveyor passes around the periphery of the sprocket wheels.

Referring to Fig. 10, it will be seen that a cylindrical transfer wheel 70 is disposed at the base of the chute 63 and suitably mounted for rotation on its axis in timed relation with the rotation of sprocket wheels 25, 26, the transfer wheel being driven from the power shaft 19 which drives the machine of the present invention, the drive connection between the power shaft 19 and the wrapping machine being not shown in the drawings. Said transfer wheel 70 in its periphery is formed with a plurality of axially extending U-shaped grooves 72 of a size and shape to receive therein one stack of mints delivered by the conveyor 39 and cooperates with an apron 73 to deliver the stacked mints to a receiving pocket 74 carried by a conveyor 75 of the wrapping machine of the type hereinbefore referred to. The transfer wheel 70 is given an intermittent rotary motion and, in the form illustrated, is periodically rotated $\frac{1}{4}$ turn so as to transfer the mints received from the chute 63 from the position 72a of pocket 72 to the position 72b in Fig. 10, at which latter position the stacked and color-arranged mints are deposited in the pocket 74 of the automatic wrapping machine.

While I have shown and described a preferred embodiment of my invention it will be understood that various modifications may be made therein within the range of engineering and mechanical skill without departing from the spirit of the invention or from the scope of the following claims.

What I claim is:

1. A machine of the character set forth, comprising a longitudinally movable conveyor, means providing with said conveyor a plurality of longitudinally and transversely disposed rows of article-receiving pockets, a plurality of article delivery platforms disposed in longitudinal spaced relation along the line of travel of said conveyor, at which platforms articles are deliverable to the receiving pockets, and means for selectively masking the pockets in predetermined rows to prevent the entry of articles thereto at predetermined delivery platforms.

2. A machine according to claim 1, wherein the means for masking the pockets have downwardly sloping side

walls for promoting entry of articles into the unmasked pockets.

3. A machine according to claim 1, wherein the means which provide with the conveyor the article-receiving pockets comprises fixed and movable components, the fixed components being disposed in parallel spaced relation longitudinally of the conveyor, and the movable components being carried by the conveyor and having projections which extend and are movable between the fixed components.

4. A machine according to claim 3, wherein the transversely movable components carried by the conveyor project outwardly from and are spaced longitudinally of the conveyor, the projections on said movable components providing with the fixed components the article-receiving pockets.

5. A machine of the character set forth comprising a longitudinally movable conveyor having a plurality of transverse members movable therewith, each said transverse member having a plurality of upstanding fingers, a plurality of vertically disposed longitudinal walls disposed above said conveyor and providing with said fingers a plurality of longitudinally and transversely disposed rows of pockets, a plurality of article delivery hoppers disposed in longitudinal spaced relation along the line of travel of said conveyor, from which hoppers articles may be fed into said pockets, and hoods closing off the spaces between some of said longitudinal walls adjacent the base of one of said hoppers to prevent the entry of articles into certain longitudinal rows of the pockets beneath such hoods.

6. A machine according to claim 5, wherein the hoods for masking the pockets are mounted on the vertically disposed longitudinal walls.

7. A machine according to claim 5, wherein there are hoods closing off the spaces between other of the longitudinal walls adjacent the base of another of said hoppers to prevent the entry of articles into other longitudinal rows of pockets beneath such hoods.

8. A machine according to claim 5, wherein the hoods adjacent the base of one of the hoppers span the spaces between alternate pairs of said walls to close off alternate longitudinal rows of pockets and prevent the entry of articles thereinto, and hoods adjacent the base of another of said hoppers span the spaces between the other alternate pairs of walls.
